UNITED STATES PATENT OFFICE.

JACOB LORENZO BROWN, OF RAHWAY, NEW JERSEY.

RAILWAY-CAR BRAKE.

SPECIFICATION forming part of Letters Patent No. 357,455, dated February 8, 1887.

Application filed June 1, 1886. Serial No. 203,804. (No model.)

To all whom it may concern:

Be it known that I, JACOB LORENZO BROWN, of Rahway, in the State of New Jersey, have invented certain new and useful Improvements in Mechanism for Railway-Brakes; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to that class of car-brakes commonly known as "continuous" or "train" brakes, in which the braking-power is conveyed from car to car throughout the train and operated from some point (generally the engine) in its length. In this invention the braking-power is derived from the rotation of the car-axles and applied to one or more of the cars, so that by manipulating the apparatus from any desired point the brakes may be applied or released throughout the train.

Heretofore the apparatus used for producing the results reached by this invention have been so complicated and difficult to operate that it has prevented their general introduction upon the rolling-stock of railways.

The object of my invention is, therefore, to simplify and reduce the cost of the apparatus, while still retaining its efficiency to such an extent as to make it not only the cheapest, but among the best braking mechanisms of its class offered to railway-managers; and the invention consists in the means employed for converting the power gained from the rotation of the axles into direct pressure upon the peripheries of the wheels of all the brake-shoes; also, in the means used for conveying the power required to put the braking mechanism in operation on one car to all the other cars of the train; and, further, in certain details of construction, which will be hereinafter fully described.

In the accompanying drawings, Figure 1 is a bottom plan showing the general arrangement of the braking apparatus and its means of connection with similar devices upon the adjoining car of the train. Fig. 2 is a vertical and longitudinal section on line 2 2 of Fig. 1, il-

lustrating upon an enlarged scale the power mechanism applied to the axle and the devices for operating it. Fig. 3 is a rear elevation, in perspective, of one of the car-axles and the gearing by which the brakes are applied. Fig. 4 is a transverse section showing the truck-beam, the axle, the brake-operating gear, and the operating-lever.

In these several figures, A denotes the car-floor, under each end of which is placed a truck, B. These trucks may be of the ordinary construction, as the brake-operating mechanism is readily attached to them without material change, thus making it applicable to the cars now in general use without material change in their construction.

In describing the brake-operating mechanism it will be understood as applied to one truck of a car, although it is evident that, if desired, it may be attached to both trucks of every car in the train; but experience shows that this will be unnecessary, except in special cases where trains are worked on heavy grades.

C represents the truck-beam, and D the axles, on one of which is placed the pinion E, by which the braking-power is transmitted to the brake-shoes. This pinion E slides on the axle, and is provided with projecting lugs a, which may be made to engage with the projecting arms of a cross-bar, a', firmly secured to the axle, so that when the lugs a engage with said arms the pinion revolves with the axle. Upon the opposite side of the pinion from the lugs is formed a collar, a'', having a grooved periphery, which receives a clutch or the forked end of an operating-lever, F, actuated by means to be hereinafter described.

Secured to the truck-beam by suitable bolts is a bracket, G, provided with journal-bearings, in which revolves the winding shaft or drum H, upon which is secured the fixed collar b, and against this collar is placed the gear-wheel I, upon the opposite side of which from the collar b is placed a loose collar, b', held in contact with the gear-wheel by the spring b'', coiled around the shaft H, and having its tension upon the loose collar regulated by a nut or other suitable device upon the end of said shaft. It will thus be seen that when the pinion E is in gear with the wheel I the latter will be rotated by said pinion; but the winding-shaft will not

be rotated if the resistance is greater than the friction of the collars b and b' upon the gear-wheel. By this arrangement the power applied to the brake-shoes may be so adjusted as 5 to prevent skidding the wheels and injuring them by the formation of flat spots upon their heads.

Attached to the winding-shaft H is the chain K, which passes around a sheave, c, in the 10 outer end of equalizing-lever L, pivoted at a suitable point between the two trucks to the car-bottom A. This chain is then carried back to the end of the car, where, if the car be the first or last in the train, it may be secured, so 15 as to form a fulcrum-point for the action of the brakes; but if the car occupy an intermediate position in the train it is connected by a suitable coupling with the brake mechanism of the adjoining car or cars.

20 To each truck-beam is secured a bar, M, at the opposite end of which are pivoted the brake-levers d d', one of which, d', carries at its free end a sheave, d''. The brake-chain N is attached at its opposite ends to the free ends 25 of levers d, passing around the sheaves d'' and around the sheaves c' and c'' in the equalizing-lever L. It will, therefore, be apparent that any movement imparted to the equalizing-lever L by the chain K will be transferred through 30 the brake-chain N to the brake-levers, and by them, through suitable connections, to the brake-beams O, by which the brake-shoes are applied to the wheels.

In order to set the hereinbefore-described 35 mechanism in operation and to automatically throw them out of connection and retain them in that condition when the brake is no longer required, the devices hereinafter described are employed.

40 To the upper end of the forked lever F is attached one end of a spring, e, the other end of which may be secured to the car-bottom or other suitable point of attachment. The tendency of this spring is to hold the lever in such 45 a position as to keep the pinion E out of gear with the wheel I, thus preventing the brake-shoes from being brought into contact with the wheels until the position of the lever F and pinion is changed or shifted, so as to bring the 50 pinion into gear with the wheel. To accomplish this result, a chain, P, is attached to the upper end of the lever F, passes thence around the sheave c', attached to the car-bottom and to one end of the car, where it may be connected 55 with a winding-shaft or other suitable operating device, or with a corresponding chain carried by the next adjoining car. It will be apparent that power applied to this chain P will cause the lever F to throw the 60 pinion on the axle into engagement with the wheel upon the winding-shaft, and that the rotation of the latter will, through the chain K and its connections, apply the brakes, which will be retained in contact with the wheels until the tension upon chain P is relaxed, when 65 the spring e will instantly reverse the position of lever F, throwing the pinion out of engage-

ment with the gear-wheel upon the winding-shaft and releasing the brakes.

As it is desirable to provide means for controlling the operation of the brakes from either end of the same car or from any car in the train the following devices are employed for that purpose. A lever, R, is pivoted to the bottom of the car, as shown in Fig. 1, to one 70 end of which lever is attached the chain or rod P', which rod extends to the opposite end of the car from that reached by the rod or chain P, said connection P' being provided with the same means for operating it from the 75 end of the car or attaching to the adjacent car as the connection P. By these means it will be obvious that the action of the braking mechanism may be controlled from either end of a car or from any car provided with this 80 apparatus in a train.

As it is sometimes desirable to connect the brake-power of one car to the brake apparatus of the next car in the same train, which may or may not be provided with the mechanism 90 hereinbefore described for taking braking-power from the axle, I pivot to the bottom of the car a lever, S, one end of which is connected with the chain K and its opposite end with a chain, K', which extends to the opposite end of the car from that reached by the chain K, and like that may be connected to the 95 braking apparatus of an adjoining car, thus conveying the brake-power generated upon one car to its neighbor either in front or rear. 100

I am aware that many plans have been suggested for accomplishing the object sought in this invention. I do not therefore claim, broadly, a continuous or train brake, but only the special mechanism by which I accomplish 105 the end sought.

Having thus described my invention, I claim as new, and desire to secure by Letters Patent, the following:

1. In a mechanism for operating car-brakes, 110 the combination of a sliding pinion upon a car-axle with a frictionally-held gear-wheel mounted upon a winding-shaft, a chain winding upon said shaft, and suitable mechanism for connecting said chain with the car-brakes, 115 as set forth.

2. The combination, in mechanism for operating car-brakes, of the sliding pinion upon the axle, the friction-held gear upon the winding-shaft, the lever by which such pinion is operated, the spring acting upon said lever to hold the pinion normally out of engagement with the winding-shaft gear, and the chains and the appliances by which the position of the pinion is shifted to apply the brakes, substantially as 125 specified.

3. In a car-brake, the bracket G, secured to the truck-beam, winding-shaft H, revolving in journal-bearings in said bracket, fixed collar b, loose collar b', and adjusting-spring b'', in 130 combination with the loose gear-wheel I, and sliding pinion E, arranged to wind up the power-applying chain K in applying the brakes, as specified.

4. In a continuous or train brake mechanism, the combination of the power devices with the equalizing-lever L, lever S, chains K and K', and brake-chain N, all arranged and operating substantially as specified.

5. In a continuous or train brake, the combination, with the power mechanism, of the lever F, spring e, chains P and P', and lever R, said chains being arranged to connect with the

brake-operating devices of an adjoining car, to in the manner set forth.

In testimony that I claim the foregoing as my own I affix my signature in presence of two witnesses.

JACOB LORENZO BROWN.
